UNITED STATES PATENT OFFICE.

HOWARD F. GAWNE, OF EUCLID VILLAGE, OHIO.

INTERNAL-COMBUSTION ENGINE.

Application filed May 8, 1922. Serial No. 559,342.

To all whom it may concern:

Be it known that I, HOWARD F. GAWNE, a citizen of the United States, residing at Euclid village, in the county of Cuyahoga and State of Ohio, have invented certain new and useful Improvements in Internal-Combustion Engines, of which the following is a specification.

This invention relates to internal combustion engines, and has for its object to provide an improved engine of the four cycle double acting type, and in which sleeve valves are employed for controlling the fuel supply and the exhaust, and this object is accomplished by or is embodied in a novel construction with respect to a cylinder head which telescopes within a hollow piston, without the use of the conventional piston rod, stuffing box and cross head, and all of the ports controlling the inlet and exhaust to and from opposite sides of the piston are governed by means of two moving sleeves operated by a valve shaft. The engine therefore has the advantages and effectiveness of the double acting type and also of the sleeve valve type.

One embodiment of the invention is illustrated in the accompanying drawings in which Fig. 1 is a vertical or longitudinal cross section of the engine. Fig. 2 is a section on the line 2—2 of Fig. 1. Fig. 3 is a vertical section on the line 3—3 of Fig. 1. Fig. 4 is a vertical section of the piston. Fig. 5 is a section on the line 5—5 of Fig. 4. Fig. 6 is an elevation of a fixed sleeve having ports. Fig. 7 is an elevation of the same, turned 90°, and looking in the direction of the arrow toward Fig. 6. Fig. 8 is an end view of the same. Fig. 9 is an elevation of the lower or inner cylinder head. Fig. 10 is a bottom end view of the same. Fig. 11 is an elevation of the outer valve sleeve. Fig. 12 is an elevation of the same turned 90° and looking in the direction of the arrow toward Fig. 11. Fig. 13 is a bottom end view of the same. Fig. 14 is an elevation of the inner sleeve valve. Fig. 15 is an elevation of the same turned 90° and looking in the direction of the arrow toward Fig. 14. Fig. 16 is a bottom end view of the inner sleeve valve.

The outer cylinder wall is indicated at 16, and this is cored for the water jacket 17 which may be suitably disposed for cooling

purposes. The outer head or crown 18 is depressed to provide space for one of the spark plugs 19, which is set in a suitable hole in the cupped head 20 which also forms the inner guide for the upper end of the valve sleeves, the outer guide consisting of the opposite wall section of the cylinder. The cylinder is mounted on a crank case 21 which may be made in sections, and across which extends the crank shaft 22 the intermediate section of which has a flange 23 projecting inwardly and supporting a fixed sleeve 15 which is flanged at the bottom and may be suitably mounted on or bolted to the flange 23. This fixed sleeve projects upwardly within the cylinder 16 to near the top thereof, and is spaced therefrom, and is provided with a lower inlet port 15^a and exhaust port 15^b and an upper inlet 15^c and exhaust port 15^d. On one side of the cylinder is an intake manifold 24, with a branch 25 in line with the port 15^a and a branch 26 in line with the port 15^c. The opposite side of the cylinder has an exhaust manifold 27 with a branch 28 in line with the port 15^b and another branch 29 in line with the port 15^d.

Also mounted on the flange 23 or on a spacing plate 23^a fixed thereto is an inner or lower head 10. This is hollow, and the lower parts of its sides are slotted as indicated at 10^a. It may be held in place by bolts through lugs 10^b at the bottom thereof; and this head is spaced from the fixed sleeve 15 into which it projects, and it has suitable grooves 10^c for packing rings.

The piston head is indicated at 1, and it is fixed to or provided with a skirt or cylindrical extension 2 which reciprocates in the space between the head 10 and an inner sleeve valve 3. The skirt of the piston has bearings 2^a for the wrist pin 2^b by which the connecting rod 30 is connected to the crank 31 of the crank shaft 22, said bearings being connected by knuckles or boss brackets 12 to the shell or skirt of the piston, and these knuckles extend and work through the slots 10^a in the sides of the lower cylinder head, so that the wrist pin and connecting rod may be positioned inside of said head. This construction produces a combustion chamber on each side of, or above and below, the piston head 1, and the piston is reciprocated by the combustion of fuel in these chambers.

The skirt of the piston has on one side an elongated inlet slot 2^b, and on the opposite side an elongated exhaust slot 2^c, which may be connected to the inlet and exhaust manifolds by the ports in the sleeve valves.

The inner valve 3 has a lower inlet port 3^a and exhaust port 3^b and an upper inlet port 3^c and exhaust port 3^d, and this sleeve valve reciprocates between the fixed sleeve 15 and the skirt 2 of the piston.

The outer sleeve valve 4 has a lower inlet port 4^a and exhaust port 4^b and an upper inlet port 4^c and exhaust port 4^d, and this valve reciprocates between the fixed sleeve 15 and the cylinder wall 16.

Each valve is operated by a knuckle connection 33 to a connecting rod 34 and valve crank shaft 35 driven by gearing 36 from the main crank shaft 22, properly set and timed to produce the operations to be described. The lower end of the sleeve 15 is slotted in at 15^e for the knuckle of the inner sleeve.

The oil system includes an oil pump 40 driven from the valve shaft and delivering through a pipe 41 to an annular chamber 42 which has a port 43 adapted to supply oil to or through small holes 44^a in the outer sleeve, 45^a in the fixed sleeve, 46^a in the inner sleeve to the adjacent surfaces of these parts respectively, the holes in the valve sleeves being sufficiently large to give time for oil to enter between the contacting surfaces of the sleeves as the parts reciprocate, the various ports being so located that they will register to provide an oil passage during part of each reciprocation. That is, they are all in the same longitudinal line, but they are out of line with the fuel ports. The respective sleeves are also provided with ports 44, 45, 46 and the piston has a port 47 so located that they all register at the firing time of the lower chamber with a recess in the cylinder wall in which is set, sidewise, the lower spark plug 50, as shown in Fig. 2, so that the charge within the barrel 2 of the piston may be fired.

The throw of the valve shaft cranks, and the ports in the various valves and sleeves are such, that as the sleeves and the piston reciprocate the cycle of the engine will be maintained. In one position, the inlet passage 26 is connected through the ports 4^c in the outer valve, 15^c in the fixed sleeve, 55 and 3^c in the inner sleeve, to the upper combustion chamber, on the suction stroke, and during compression these ports are closed and remain closed during the firing stroke, at the end of which the ports 3^a, 15^d and 4^d are registered to permit exhaust into the exhaust passage 27.

In the lower combustion chamber the corresponding operation occurs. At the suction stroke the ports 4^a, 15^a and 3^a are registered with a slot 2^e in the piston, thereby admit-

ting a charge from the inlet 25 to the lower chamber between the piston head and the fixed head 10, and after compression and firing the exhaust takes place through the slot 2^e, ports 3^b, 15^b and 4^b to the exhaust 70 passage 28, this position being shown in Fig. 1.

The various other adjacent and attachments of the engine may be such as are suitable or as are found in existing gas engine 75 practice, and no description is considered necessary. The invention is not limited to the particular construction shown but may be varied in different ways, within the scope 80 of the invention.

I claim:

1. In a double acting internal combustion engine, the combination of a cylinder having inlet and exhaust ports at each end thereof, a fixed head projecting into one end of the cylinder and spaced from the wall thereof, a hollow piston in the cylinder, fitting around and reciprocating on said fixed head, a fixed sleeve between the piston and the cylinder wall, an inner sleeve valve between the piston and the fixed sleeve, an outer sleeve valve between the fixed sleeve and the cylinder wall, said sleeve and sleeve valves all having spaced sets of inlet and exhaust ports adapted to be registered with the cylinder ports, and the piston having inlet and exhaust slots registering with the said ports, and means to operate said valves. 90

2. In a double acting internal combustion engine, the combination with a cylinder and a hollow piston therein, of sleeve valves surrounding the piston and having ports controlling inlet to and exhaust from opposite sides of the piston, and an igniter set in the side of the cylinder, the piston and sleeve valves having openings which register to connect the interior of the piston and the igniter at the firing period. 100

3. In a double acting internal combustion engine, the combination of a cylinder having inlet and exhaust ports at each end thereof, a fixed head projecting into one end of the cylinder and spaced from the wall thereof, a hollow piston in the cylinder, fitting around and reciprocating on said fixed head, a fixed sleeve between the piston and the cylinder wall, an inner sleeve valve between the piston and the fixed sleeve, an outer sleeve valve between the fixed sleeve and the cylinder wall, said sleeve and sleeve valves all having spaced sets of inlet and exhaust ports adapted to be registered with the cylinder ports, and the piston having inlet and exhaust slots registering with the said ports, and means to operate said valves, and an igniter set in the side of the cylinder, said piston fixed sleeve and sleeve valves having openings which register and connect the interior of the piston and the igniter at the 110

120

125

130

135

140

145

150

4. In a double acting engine, the combination with a cylinder, of a hollow head fitting in one end of the cylinder and spaced therefrom, the side walls of said head being slotted, and a hollow piston telescoping on said head and reciprocating in the cylinder, and a connecting rod having a wrist pin attachment to the side walls of the piston, said attachment extending through the slots.
5. In a double acting engine, the combination with a cylinder, of a hollow head fitting in one end of the cylinder and spaced therefrom, the side walls of said head being slotted, a hollow piston telescoping on said head and reciprocating in the cylinder, a connecting rod having a wrist pin attachment to the side walls of the piston, said attachment extending through the slots, and sleeve valves reciprocating between the piston and the wall of the cylinder and controlling the inlet to and the exhaust from the same.
6. In a double acting engine, the combination with a cylinder, of a hollow head fitting in one end of the cylinder and spaced therefrom, the side walls of said head being slotted, a hollow piston telescoping on said head and reciprocating in the cylinder, a connecting rod having a wrist pin attachment to the side walls of the piston, said attachment extending through the slots, and sleeve valves reciprocating between the piston and the wall of the cylinder and controlling the inlet to and the exhaust from the same, the end of the cylinder opposite the said head having an annular guide for the ends of the sleeve valves.
7. In a double acting internal combustion engine, the combination of a cylinder having inlet and exhaust ports at each end thereof, a hollow head projecting into the cylinder and spaced at its sides from the cylinder wall, a fixed sleeve extending in the space between said head and the cylinder wall and through-out the length of the cylinder, a hollow piston reciprocating in the cylinder and having a tubular skirt working in the space between the fixed sleeve and said head, an inner sleeve valve extending through-out the length of the cylinder and working between the piston and the fixed sleeve, and an outer sleeve valve extending through-out the length of the cylinder and working between the fixed sleeve and the cylinder wall, said skirt, sleeve and sleeve valves having ports adapted to register with said inlet and outlet ports in the cylinder.
8. A double acting internal combustion engine having a hollow piston forming an explosion chamber, sleeve valves surrounding said piston, said valves and piston having openings adapted to communicate with said chamber, a spark plug in the side wall of the cylinder and with which said openings register at the firing period, and an oil passage in the cylinder wall, having a port opening into said ports in the sleeve valves and piston.
9. In a double acting internal combustion engine, the combination of a cylinder having inlet and exhaust ports at each end thereof, a hollow fixed head projecting into one end of the cylinder and spaced from the side wall thereof, said head having slotted side walls, a hollow piston in the cylinder, having side walls telescoping on said head, a connecting rod working in the hollow head and connected to the side walls of the piston through said slots, a fixed sleeve spaced from said head and surrounding the same and having a slot, an inner sleeve valve extending within the cylinder and between said fixed sleeve and the piston, and an outer sleeve valve extending within the cylinder and between said fixed sleeve and the cylinder wall, the inner sleeve valve having a knuckle extending through the slot in the fixed sleeve, said sleeve valves, sleeve and piston having ports adapted to register with the inlet and exhaust ports in the cylinder.
10. In an internal combustion engine, the combination with a cylinder, the head in one end of the cylinder being provided with an interior space for the passage of the connecting rod end, the head having no opening in its transverse wall, a skirted piston in the cylinder, means for attaching the connecting rod end to the skirt of the piston, the piston being exterior to the head, and a system of valve sleeves concentric with the head and adapted to control the flow of gases to and from the spaces on the opposite sides of the transverse wall of the piston.

In testimony whereof, I affix my signature in presence of two witnesses.

HOWARD F. GAWNE.
